PORTABLE CHEMICAL TOILET

David B. Harding, Grosse Pointe Woods, Mich., assignor
to Sani-Jon of America, Inc., Warren, Mich.

Filed Apr. 3, 1967, Ser. No. 6,480

Term of patent 14 years

(Cl. D23—48)

FIG. 1 is a top plan view of a portable chemical toilet, showing my new design.

FIG. 2 is a top plan view of the bottom portion thereof, the top being omitted for convenience of illustration.

FIG. 3 is a front, elevational view.

FIG. 4 is a right side elevational view thereof, the left side being a mirror image of the right side shown.

FIG. 5 is a rear elevational view thereof.

FIG. 6 is a perspective view thereof.

FIG. 7 is an enlarged, fragmentary, cross-sectional view taken in the direction of 7—7 of FIG. 4.

I claim:

The ornamental design for a portable chemical toilet, as shown and described.
